UNITED STATES PATENT OFFICE.

PERES E. DIX, OF DELAWARE, OHIO.

PITMAN CONNECTION.

SPECIFICATION forming part of Letters Patent No. 760,855, dated May 24, 1904.

Application filed February 11, 1904. Serial No. 193,203. (No model.)

To all whom it may concern:

Be it known that I, PERES E. DIX, a citizen of the United States, residing at Delaware, in the county of Delaware and State of Ohio, have 5 invented new and useful Improvements in Pitman Connections, of which the following is a specification.

The invention relates to pitman connections, and has for its object to provide simple, easily-assembled, and readily-adjustable means for connecting the end of a pitman with a reciprocating cutter-bar of a mowing-machine or with the like.

The invention consists in the construction 15 hereinafter described and pointed out.

In the accompanying drawings, Figure 1 is a perspective of the improvement applied to a cutter-bar. Fig. 2 is a longitudinal section of the same. Fig. 3 is a similar section taken 20 transversely to the view in Fig. 1, and Fig. 4 is a transverse section taken approximately at right angles to the view in Fig. 3.

Numerals 1 indicates a pitman, and 2 a cutter-bar or like part to be reciprocated thereby, as usual in mowing-machines and in other machines comprising similarly-reciprocated parts. The bar 2 has a socket 3 to receive the head 4 of the outer end of the pitman. This socket has a main chamber whose walls by 25 preference are undercut on the interior, substantially as indicated in the drawings, and said chamber or space communicates with a slot 5, in which the neck 6 of the pitman works. The vertical walls of the socket are 30 preferably undercut, as shown at 7, and the pitman-head has undercut parts 8 to engage therewith. The said parts 8 are curved from the top to bottom to provide for a movement of the head in its socket and of the neck in 35 the slot 5. The head is also curved at its end, as indicated at 9, and its sides are curved substantially as shown. The head and neck of the pitman are split, as indicated at 10.

A screw or screw-threaded bolt having a 45 frusto-conical head is denoted by 11, and a frusto-pyramidal nut by 12. A seat or suitably-shaped opening is provided between the parts of the head for the screw and nut. Preferably one end of this opening will be 50 round, and the other end, in which the wedge-shaped nut is held, will be angular to correspond with said nut. The parts are assem-

bled by placing the screw in the seat 12 and engaging it with the frusto-conical or wedge-shaped nut and then inserting the pitman-head in the socket, whereupon by suitably turning the screw the nut can be drawn further into its seat, with the effect to spread the head by crowding its sections apart, and this can also be done whenever it is desirable to 60 adjust the head to compensate for wear or whenever it is desired to disconnect the parts. Because of the undercut sides of the socket a very small expansion of the head is sufficient to prevent all danger of its accidental displacement whatever be the position of the parts.

The side walls of the slot 5 can be cut away on their exterior, as at 13, to reduce the weight. The undercut bearing-surfaces of 70 the head and the socket adjacent the neck tend to obviate friction of the neck against the walls of the neck-receiving slot.

Having described my invention, what I claim as new, and desire to secure by Letters 75 Patent, is—

1. The combination of a pitman having an expandible head, and the bar having an open socket and a comparatively narrow slot to receive the head and neck of the pitman respectively.

2. The combination of the pitman having an expandible head, and the bar having an open socket to receive the head, said socket having undercut walls at its sides.

3. In a pitman the head having the undercut cheeks in combination with a part having a corresponding undercut socket.

4. In a pitman, the head having cheeks 8 and a part having socket with an open side, 90 said cheeks being rounded in a direction from the open side of the socket to the opposite side.

5. The combination of a pitman having a split head, and the bar having an open socket 95 to receive the head, a screw and a wedge-shaped nut to expand said head.

In testimony whereof I have hereunto set my hand in presence of two subscribing witnesses.

PERES E. DIX.
